COVER FOR A TRUCK BED

Robert L. Gardner, Newport, Ark., assignor to Gladys Hurley, doing business as Walter F. Hurley Gin, Diaz, Ark.

Filed Apr. 23, 1968, Ser. No. 11,579

Term of patent 14 years

U.S. Cl. D14—27
Int. Cl. D12—14

FIG. 1

FIG. 2

FIG. 1 is a top view of a cover for a truck bed showing my new design.

FIG. 2 is a side elevational view thereof.

FIG. 3 is a sectional view of my new design taken as on the line III—III of FIG. 1.

The truck, shown in broken lines, is included for illustrative purposes only.

I claim:

The ornamental design for a cover for a truck bed, as shown and described.
